DESIGN FOR AN IMPLEMENT SHED

Elmer F. Clark, Kansas City, Mo., assignor to
Butler Manufacturing Company, Kansas City,
Mo., a corporation of Missouri

Application May 25, 1944, Serial No. 113,752

Term of patent 14 years

(Cl. D13—1)

To all whom it may concern:

Be it known that I, Elmer F. Clark, a citizen of the United States, residing at Kansas City, in the county of Jackson and State of Missouri, have invented a new, original, and ornamental Design for an Implement Shed, of which the following is a specification, reference being had to the accompanying drawing, forming part thereof, in which

Fig. 1 is a perspective view showing the front and one end of a shed embodying my new design, and

Fig. 2 is a perspective view showing the back and one end of the shed.

I claim:

The ornamental design for an implement shed, substantially as shown.

ELMER F. CLARK.
